DES. 2104

Garrison Smith and Henry Brown, of Philadelphia, Penna.
assignors to

Smith, Wells & Company, of Rogers Ford, Penna.
Letters Patent No. 2106 - Dated June 27-1865.

Design for the panel of a stove.

The schedule referred to in these Letters Patent and making part of the same.

Wall upon which it may concern.

Be it known that we, G. Smith and H.C. Brown, both of Philadelphia, County of Philadelphia, State of Pennsylvania, have invented or produced a new and original design for the panel of a stove, and we do hereby declare the accompanying drawing with the following explanation of the same, to form a full, clear and exact description of the said design.

For the drawing, the figure represents the panel of a stove, in the centre of which is a base, surrounded by an ornamental oval border, and on the face of the panel round the central ornament are the ornamental foliated figures shown in the drawing.

We claim:

The ornamental figures and forms shown in and by the accompanying drawing, the whole forming an ornamental design for a panel of a stove.

In testimony whereof we have signed our names to this specification in the presence of two subscribing witnesses.
